(57) **CLAIM**

The ornamental design for a cap, as shown and described.

DESCRIPTION

FIG. 1 is a front, top, and right side perspective view of a cap;
 FIG. 2 is a top plan view thereof;
 FIG. 3 is a front elevational view thereof;
 FIG. 4 is a rear elevational view thereof;
 FIG. 5 is a right side elevational view thereof; and,
 FIG. 6 is a left side elevational view thereof.
 The broken lines in the drawings depict environmental subject matter only and form no part of the claimed design.
